CLAIM

The ornamental design for a light, as shown and described.

DESCRIPTION

FIG. 1 shows a front perspective view of a light;
FIG. 2 shows a rear perspective view of a light;
FIG. 3 shows a front view of the light with a smart phone of FIG. 1;
FIG. 4 shows a right rear view of the light with a smart phone of FIG. 1;
FIG. 5 shows top view of the light of FIG. 1;
FIG. 6 shows bottom view of the light of FIG. 1;
FIG. 7 shows the right side of the light of FIG. 1; and,
FIG. 8 shows the left side of the light of FIG. 1.
The broken lines depict portions of the light that form no part of the claimed design.
